UNITED STATES PATENT OFFICE.

JOSIAH H. SUTTER, OF WICHITA, KANSAS.

HEATING APPARATUS.

Application filed January 27, 1928. Serial No. 248,901.

My invention relates to improvements in heating apparatus.

It is one of the objects of my invention to provide novel means for bringing air from a room into a stove or furnace, heating the air therein and then discharging the heated air from the stove into the room.

A further object of my invention is to provide a novel air heater, which is adapted for insertion through an opening in a stove or furnace, and which is provided with novel means for conveying air into the furnace or stove, out of contact with the gaseous products of combustion therein, heating the air so conveyed and discharging it into the room outside the stove or furnace.

Still another object of my invention is to provide a novel air heater which is simple, cheap, durable, not likely to get out of order, which is readily adapted for insertion into and removal from the top opening in a stove or furnace, and which is efficient in its operation.

The novel features of my invention are hereinafter fully described and claimed.

In the accompanying drawing, which illustrates the preferred embodiment of my invention,

Fig. 1 is a front elevation, partly broken away, showing a stove of the usual cannon type provided with my improvement.

Fig. 2 is an enlarged, central, vertical sectional view of my improved air heater, partly broken away.

Fig. 3 is a section on the line 3—3 of Fig. 2.

Fig. 4 is a view, partly in vertical section, partly in elevation and partly broken away of the inner conductor and a portion of the bottom of the outer conductor attached thereto.

Similar reference characters designate similar parts in the different views.

My improved air heater comprises an outer conductor for air having a cylindrical upper portion 1 adapted for insertion through the top opening 2 of a stove 3, which may be of any usual type, the one shown being an ordinary cannon heating stove. The portion 1 is provided with an annular peripheral groove 4 adapted to receive the stove top 5, such portion 1 being capable of being compressed so as to be passed through the opening 2, and having resiliency sufficient to cause it to spring out into engagement with the top 5 when the latter registers with the groove

4, whereby the heater is supported by the stove top.

The lower portion of the outer conductor is, preferably, downwardly flaring, and is designated by 6. The lower end of the flaring portion 6 has fitted on it a closed bottom plate 7 having an inturned annular flange 8 embracing the outer side of the flaring portion, as shown in Fig. 2.

The flaring portion 6 has an upper cylindrical portion 9 adapted for removable insertion into the lower end of the upper portion 1.

Within and spaced at its side walls from the outer conductor is an inner conductor comprising a vertical cylindrical portion 10, which extends upwardly in the outer conductor, and has an open upper end, which is, preferably, extended higher than the upper end of the outer conductor, in order to effect a strong draft of air upwardly therethrough.

The lower portion 11 of the inner conductor is downwardly flaring, and fastened at its lower end to the bottom plate 7 in any suitable manner as by riveting. The upper end of the portion 11 is cylindrical and removably fitted, preferably, in the lower end of the portion 10.

The flaring portion at its lower end is provided with peripheral intake openings 12, Fig. 4, which radially align with vertical plates 13, which are fastened at their lower ends to the top of the bottom plate 7.

In assembling the heater in a stove, the portion 1 is inserted into the opening 2, so that the top 5 enters the groove 4.

The upper end of the lower portion 6, with the plates 13 and portion 11 fastened thereto, is inserted into the lower end of the portion 1, the said portion 6 and parts attached thereto being inserted into the stove through the door 14 of the stove. The portion 10 is then slipped into the portion 1 and fitted over the upper end of the portion 11.

When a fire is built in the stove the heat therefrom will heat the air in the lower end of the portions 11 and 6 and the heated air will rise in the inner conductor and will be discharged into the room. This will create a downward draft of colder air through the outer conductor, such colder air entering the upper end of the portion 1, passing thence downwardly to and through the intake openings 12 and into the flaring portion 11 between the plates 13, where it will be heated and will then pass upwardly out of the

heater through the portion 10 into the room. In this manner the air in the room will be heated to a much greater extent and more quickly than could be done with the stove without the use of my heater, and without increasing the amount of fuel consumed.

The presence in the stove or furnace of my heater will not interfere in any manner with the feeding of fuel or the combustion thereof.

10 I do not limit my invention to the structure shown and described, as many modifications, within the scope of the appended claims, may be made without departing from the spirit of my invention.

15 What I claim is:—

1. In an air heater, two air conductors, one within the other and having its side walls spaced therefrom and having an open upper end and a downwardly flaring lower end having intake openings and resting against the bottom of the outer conductor, the latter having an open upper end and a closed flaring lower end adapted for insertion into a stove or furnace, and upwardly tapering radial plates extending from the bottom of the outer conductor into the flaring end of the inner conductor.

2. In an air heater, two air conductors, one within the other and having its side walls spaced therefrom and having an open upper end and a downwardly flaring lower end resting on the bottom of the outer conductor and provided with peripheral intake openings, the outer conductor having an open upper

35 end and a closed downwardly flaring lower end adapted to be inserted into a stove or furnace, and upwardly tapering radial plates

extending from the bottom of the outer conductor into the flaring end of the inner conductor and respectively disposed at their 40 outer edges radially with said openings.

3. In an air heater, two air conductors, one within the other and having its side walls spaced therefrom and having an open upper end and a downwardly flaring lower end resting on the bottom of the outer conductor and having peripheral intake openings, the inner conductor projecting higher than the outer conductor, the latter having an open upper end and a closed downwardly flaring lower end adapted for insertion into a stove 45 or furnace, and plates extending from the bottom of said outer conductor into the flaring end of the inner conductor and radially alining respectively with said openings.

4. The combination with a stove having a top opening, of two air conductors, one within the other and spaced at its side walls therefrom, both conductors having open upper ends, the inner conductor extending higher than the outer conductor and having a downwardly flaring lower end resting on the bottom of the outer conductor and having peripheral intake openings, the outer conductor having a downwardly flaring lower closed 50 end disposed in said stove, the outer conductor extending through said top opening, and plates extending from the bottom of said outer conductor into the flaring end of the inner conductor and radially alining respectively with said peripheral openings.

In testimony whereof I have signed my name to this specification.

JOSIAH H. SUTTER.
